FIG-3-

UNITED STATES PATENT OFFICE.

HENRY C. MANCHESTER AND SAMUEL S. RIEGEL, OF SCRANTON, PENNSYLVANIA.

DRIFTING-VALVE FOR LOCOMOTIVE-ENGINES.

1,104,306.

Specification of Letters Patent. Patented July 21, 1914.

Application filed August 21, 1913. Serial No. 785,888.

To all whom it may concern:

Be it known that we, HENRY C. MANCHESTER and SAMUEL S. RIEGEL, both of Scranton, in the county of Lackawanna and State 5 of Pennsylvania, have jointly invented a certain new and useful Improvement in Drifting-Valves for Locomotive-Engines, of which improvement the following is a specification.

10 This invention relates to valve devices for controlling the supply of a limited quantity of steam to the valve chest and cylinders of a locomotive engine when drifting, or running with throttle closed, for the purpose 15 of preventing the formation of a vacuum in the cylinders and insuring a sufficient lubrication; the object of the invention being to provide an improved valve device of this character, which shall be of simple construction, readily applicable to existing engines, and shall operate automatically, under the opposing pressures of the valve chest or cylinders and the live steam from the boiler, to close when the throttle is open, and to open 25 and permit a small quantity of steam to flow to the cylinders when the supply of steam through the throttle is cut off and the engine continues running.

The improvement claimed is hereinafter 30 fully set forth.

In the accompanying drawings: Figure 1 is a central section of one form of valve device embodying our improvement; Fig. 2, a horizontal section of the same, taken on the 35 line *a a* of Fig. 1; Fig. 3, a section similar to Fig. 1, but showing a structural modification; and Fig. 4, a horizontal section taken on the line *b b* of Fig. 3.

As shown in the drawings, our improved 40 valve device comprises a casing having connections adapted to communicate respectively with the valve chest, or engine cylinders, and a live steam supply from the boiler, and containing a valve subject on one 45 side to the pressure from the valve chest tending to close the same, and on the opposite side to live steam pressure tending to open said valve, a portion of its area being exposed to the atmosphere.

50 According to the preferred construction, the valve casing consists of a body portion, 5, a cap portion, 5^a, having a cylindrical projection, 5^b, and an annular chamber, 5^c, having a cylindrical bore concentric with the projection, 5^b. The hollow cylindrical member, 5^c, may, for convenience, be formed

separate from the shell or body, 5, and be inserted through an opening therein, in which position it is securely clamped by the cap member, 5^a, either with bolts, as indicated in Fig. 1, or with a screw connection, as shown in Fig. 3. The body, 5, of the valve casing, 60 communicates with the cylinder or valve chest of the locomotive, through a lateral pipe or nozzle, 7.

The valve, 6, is in the form of an inverted cup with a closed top and cylindrical side wall, 6^a, adapted for a sliding fit within the annular space between the parts, 5^b and 5^c, 70 packing rings being mounted upon the outer surface of the wall, 6^a, engaging the chamber, 5^c, and upon the projection, 5^b, engaging the inner cylindrical surface of the wall, 6^a, of the cup valve, which is provided with radial ports, 6^b, adapted to register with 75 corresponding ports, 5^d, in the cylindrical chamber, 5^c, when the valve is in its upper or open position. A passage, 5^e, formed in the cap member and its projection, 75 communicates with the space within the cup 80 valve above said projection, and may be connected at its outer end by a pipe, 8, with the live steam supply from the boiler, as indicated in Fig. 1, or the cap member may have a threaded nipple for making a direct connection to a boiler fitting, as indicated in Fig. 3. The annular chamber below the end 85 of the cylindrical wall, 6^a, of the valve, communicates with the atmosphere through passages, 5^f. A stop, 10, may be employed for 90 limiting the upward movement of the valve at the point where its ports are fully open.

It will be seen that the upper side of the valve is subject, throughout its entire area, to the pressure from the engine valve chest, 95 acting in a direction tending to move said valve to its closed position, while the under side of the valve is subject to atmospheric pressure upon its annular portion, and to live steam pressure upon the area within the 100 cup, acting in a direction tending to move said valve to its open position.

When the engine is running with the throttle open, the steam pressure from the engine valve chest, acting upon the entire 105 area of the valve, 6, forces the same down to its closed position against the live steam pressure acting upon the smaller area within the cup, and holds the valve in this position as long as the throttle remains open. 110 When, however, the main steam supply to the engine valve chest and cylinders is cut

off by closing the throttle, and the engine continues running, the movement of the pistons tends to form a vacuum in the cylinders and valve chest, and thereby rapidly diminishes the pressure acting on the upper surface of the valve, 6. As soon as this pressure is sufficiently reduced to be overbalanced by the higher live steam pressure acting upon the smaller area within the cup, the 10 valve is immediately moved upward to its open position, thereby permitting the flow of a limited amount of live steam through the casing and into the engine valve chest and cylinders. This has the advantage of 15 preventing carbonization of the oil by excessive heat, maintains efficient lubrication, and prevents the formation of a vacuum in the engine cylinders.

When the throttle is again opened, the 20 steam pressure from the engine valve chest, acting on the larger upper surface of the valve, 6, overbalances the pressure upon the smaller area on the under side of the valve, and moves the same down to its closed position; thus it appears that the operation of 25 our improved valve device is entirely automatic, and requires substantially no attention on the part of the engineer. If the engine should remain at a standstill with the 30 valve device open, the steam would continue to flow through the valve into the steam chest and cylinders until a sufficient pressure accumulated therein to close the valve, and prevent a further rise in pressure. On account of the differential areas 35 of the valve, the pressure thus admitted to the engine will be very much less than the boiler pressure and not sufficient to start the engine. If it be desired to vary the 40 maximum degree of pressure which may thus be admitted through the valve device, or in other words, to adjust the degree of pressure at which the valve will automatically close, a spring, 11, such as shown in 45 Fig. 3, may be employed, acting between the top of the valve, 6, and an adjustable screw plug, 12, mounted in the casing, and having a lock nut, 13. This spring assists the steam pressure in closing the valve, and by adjusting the screw plug, the maximum degree 50 of pressure admitted through the valve device may be limited to any desired safe degree.

For the purpose of holding the valve positively closed at any time, a threaded stem, 55 14, may be mounted in the plug, 12, and be provided with a handle, 15, outside the casing, whereby the same may be screwed down and hold the valve closed tightly upon its 60 seat, the engaging surfaces between the end of the projection, 5^b, and the under side of the valve being preferably finished to provide a seat for the same. A pressure operated drain valve, 9, as indicated in Fig. 1, 65 may be employed, if desired, for draining

out water of condensation when the steam pressure is shut off from the pipe, 8, which is connected to the lower end of the cylindrical projection, 5^b, as in Fig. 1.

We claim as our invention and desire to 70 secure by Letters Patent:

1. In a drifting valve device for locomotive engines, the combination of a casing having connections adapted to communicate respectively with a distribution valve chest 75 and a boiler steam supply, and a valve for controlling the flow of steam through the casing, said valve being subject in one direction to the pressure from the valve chest tending to close the same, and in the opposite direction to the live steam pressure from the boiler tending to open said valve.

2. In a drifting valve device for locomotive engines, the combination of a casing having connections adapted to communicate 85 respectively with a distribution valve chest and a boiler steam supply, and a valve controlling the admission of a limited quantity of live steam, said valve having means subject to the opposing pressures of the valve 90 chest and the boiler for operating the same.

3. In a drifting valve device for locomotive engines, the combination of a casing having connections adapted to communicate respectively with a distribution valve chest 95 and a boiler steam supply, and a valve for controlling the flow of steam from the latter to the former, said valve having a larger area subject to the valve chest pressure tending to close the same, and a smaller area 100 subject to the boiler pressure in the opposite direction tending to open said valve, a portion of said valve being subject to atmospheric pressure.

4. In a drifting valve device for locomotive engines, the combination of a casing having connections adapted to communicate respectively with a distribution valve chest and a boiler steam supply, and a valve subject to the opposing pressures of the valve 105 chest on one side, and to the boiler pressure and the atmosphere on the other side for controlling the flow of steam through the casing.

5. In a drifting valve device for locomotive engines, the combination of a casing having connections adapted to communicate respectively with a distribution valve chest and a boiler steam supply, a cylindrical flange within said casing, a cup shaped valve 115 120 mounted in said cylindrical flange, and a cylindrical projection extending within the cup valve.

6. In a drifting valve for locomotive engines, the combination of a casing having a cylindrical flange, and a cap portion having a cylindrical projection concentric with said flange, and a cup valve having its cylindrical wall mounted between said flange 125 and projection.

7. In a drifting valve device for locomotive engines, the combination of a casing having connections adapted to communicate respectively with a distribution valve chest and a boiler steam supply, a differential valve in said casing for controlling the flow of steam therethrough and having a larger area subject to the pressure from the valve chest tending to close the valve, and a smaller area subject to live steam pressure from the boiler tending to open the valve, and a spring acting on said valve tending to close the same.

8. In a drifting valve device for locomotive engines, the combination of a casing having connections adapted to communicate respectively with a distribution valve chest and a boiler steam supply, and a valve subject to the opposing pressures of the valve chest on one side and to the boiler steam pressure on a portion of its area and to the atmosphere on another portion of its area on the other side, and an adjustable spring acting on said valve to assist the pressure from the valve chest in closing said valve.

9. In a drifting valve device for locomo-

tive engines, the combination of a casing having connections adapted to communicate respectively with the distribution valve chest and a boiler steam supply, a piston 30 valve therein subject to the opposing fluid pressures for controlling the flow of a limited quantity of live steam to the valve chest, a spring tending to close said valve, and an adjustable plug for said spring. 35

10. In a drifting valve device for locomotive engines, the combination of a casing having connections adapted to communicate respectively with the distribution valve chest and a boiler steam supply, a piston 40 valve therein subject to the opposing fluid pressures for controlling the flow of a limited quantity of live steam to the valve chest, a spring tending to close said valve, an adjustable plug for said spring, and an 45 adjustable stem extending through said plug for holding the valve closed.
